SHIPPING DRUM

George E. Black, Sewickley, Pa., assignor to Pittsburgh Steel Drum Company, Pittsburgh, Pa., a corporation of Delaware

Application June 11, 1930. Serial No. 460,501

7 Claims. (Cl. 220—86)

This invention relates to shipping drums and more particularly to filling means therefor.

Metallic shipping drums are now commonly employed for shipping solid and semi-solid substances such as tars, pitches, rosins and the like, and in filling drums with such materials it is necessary that the materials be heated to render them sufficiently fluid to permit them to be poured into the drum. After material of the character referred to is poured into a drum, it cools and during the cooling action material shrinkage takes place. Accordingly it will be apparent that the top of the material will be spaced from the upper head of the drum and the latter will lack the support afforded by material in a completely filled drum and it further will be apparent that the drum will not be wholly filled and that a portion of the cubic capacity of the drum will not be utilized.

20 The present invention relates particularly to filling means for a drum whereby the latter may be used for the shipment of materials of the character referred to, and wherein the entire cubic capacity of the drum may be utilized.

25 A further object is to provide means of the character referred to which permits a drum to be completely filled with material of the character referred to whereby the material itself acts as supporting means for the upper head of the drum during shipment.

30 A further object is to provide means of the character described in the form of a simple readily attachable and detachable device which may be transferred from one drum to another to permit the drums to be filled.

Other objects and advantages of the invention will become apparent during the course of the following description.

In the drawing I have shown one embodiment 40 of the invention. In this showing,

Figure 1 is a central vertical sectional view through the upper end of a shipping drum showing the invention applied.

45 Figure 2 is a similar view showing the drum closed and ready for shipment, and,

Figure 3 is a detail perspective view of the filling attachment.

50 Referring to Figures 1 and 2, the numeral 10 designates the body of a drum which is connected at its upper end to a head 11 by means of a suitable seam 12. The drum, of course, is provided with a solid bottom head (not shown). The head 11 is provided with a central opening defined by a depending cylindrical flange 13, and 55 when the drum is filled and ready for shipment,

the opening is adapted to be closed by a suitable cover 14 including a cylindrical side wall 15 adapted to frictionally engage within the flange 13. The cover is further provided with an upper horizontal flange 16 which seats 60 against the upper face of the drum head.

The device forming the subject matter of the present invention comprises a preferably frusto-conical member 17 which is open at both ends as clearly shown in Figure 1. The larger end 65 of the member 17 is adapted to be arranged within the flange 13 and substantially fits the filling opening defined thereby. The lower edge of the filling member 17 is preferably arranged in the same plane as the lower edge of the 70 flange 13.

Any suitable means may be employed for supporting the filling member in the position just described. In the drawing, the member 17 is illustrated as being provided with a supporting 75 member 18 riveted or otherwise secured to the member 17 as at 19, and the supporting members is provided with an outstanding horizontal flange 20 adapted to seat upon the upper base of the head 11.

80 The operation of the device is as follows:

The cubic capacity of the filling member 17 is preferably determined according to the normal shrinkage of the particular material with which a drum is to be filled. Assuming that a drum is 85 to be employed for the shipment of pitch, the filling device is placed in the position shown in Figure 1, whereupon the pitch is heated to the proper degree of fluidity and poured into the upper end of the filling device. The pouring 90 operation is continued until the drum and the filling device are completely filled, as shown in Figure 1.

The drum is permitted to set with the filling device in position in the filling opening until 95 the material has cooled and contracted. As previously stated a filling device of the proper capacity is employed according to the normal shrinkage of the material. Accordingly the material will shrink downwardly within the filling 100 device until the surface of the material is at the level of the lower edge of the flange 13. The cover 14 thereupon may be placed in position to close the drum, and the latter is ready for shipment.

105 It has been found that when a filling device is employed which increases in size toward its lower end, as for example, when the filling device is frusto-conical, the material, as it cools, will shrink downwardly into the drum without 110

adhering to the sides of the filling device, and after the shrinkage is completed, the filling device may be removed for use in connection with another drum.

- 5 From the foregoing it will be apparent that the present invention provides novel means for filling a shipping drum in such a manner that the entire cubic capacity of the drum may be utilized without wasting space within the drum 10 as is true when the drum is filled according to the usual methods. It further will be apparent that since the drum is completely filled with material, the latter acts as supporting means for the upper head, thus tending to strengthen the 15 drum and lengthen its life.

It is to be understood that the form of the invention herewith shown and described is to be taken as a preferred example of the same and that various changes in the shape, size and arrangement of parts may be resorted to without departing from the spirit of the invention or the scope of the subjoined claims.

I claim:

1. The combination with a container having a relatively large opening in the top thereof, of a measuring filling device tapered throughout its length to decrease in size toward its upper end and having its lower end corresponding in size to and adapted to fit within said opening 30 with the smaller end thereof projecting a substantial distance above the top of the container, the capacity of said filling device being substantially equal to the shrinkage upon cooling of a quantity of a given material which at a predetermined elevated temperature is sufficient 35 to fill the container and said filling device.

2. The combination with a container having a relatively large opening in the top thereof, of a frusto-conical measuring filling device open at both ends and adapted to be arranged in vertical position over the container, the larger end of said filling device corresponding in shape to and adapted to fit within the opening in the container, the capacity of said filling device being substantially equal to the shrinkage upon cooling of a quantity of a given material which at a predetermined elevated temperature is sufficient 45 to fill the container and said filling device.

3. The combination with a container having a relatively large opening in the top thereof, of a measuring filling device having its lower end substantially fitting and adapted to be arranged in said opening and its upper end projecting a substantial distance thereabove, said device being frusto-conical in shape and decreasing in diameter toward its upper end, and means carried by said device and adapted to rest upon the top of said container for supporting said device with the lower end thereof arranged in 55 said opening, the capacity of said filling device being substantially equal to the shrinkage upon cooling of a quantity of a given material which at a predetermined elevated temperature is suffi- 60

cient to fill the container and said filling device.

4. The combination with a container having a relatively large opening in the top thereof, of a measuring filling device adapted to be arranged in operative position with its lower end in said opening and its upper end projecting a substantial distance thereabove, said device being frusto-conical in shape and decreasing in diameter toward its upper end, and a flange carried by said device and adapted to rest upon the top of the container to support the device in operative position, the capacity of said filling device being substantially equal to the shrinkage upon cooling of a quantity of a given material which at a predetermined elevated temperature is sufficient to fill the container and said filling device. 80 85 90

5. The combination with a container having a relatively large opening in the top thereof, of a measuring filling device tapered throughout its length to decrease in size toward one end and having its opposite end corresponding in size to and adapted to assume an operative position within said opening with the smaller end of said device projecting a substantial distance above the top of the container, and a flange carried by said device and spaced slightly from the larger end thereof, said flange being adapted to rest upon the top of the container to support said device in operative position, the capacity of said filling device being substantially equal to the shrinkage upon cooling of a quantity of a given material which at a predetermined elevated temperature is sufficient to fill the container and said filling device. 95 100 105 110 115

6. A measuring device of the character described comprising a body open at both ends and decreasing in size toward one end, said device being adapted to be arranged over a container having an opening in the top thereof with the larger end of said body substantially fitting and arranged in said opening, the capacity of said filling device being substantially equal to the shrinkage upon cooling of a quantity of a given material which at a predetermined elevated temperature is sufficient to fill the container and said filling device. 115 120 125

7. A measuring device of the character described comprising a frusto-conical body, an annular flange carried by said body and projecting outwardly therefrom adjacent the larger end thereof, said body being adapted to assume a vertical position with the larger end thereof arranged in a filling opening formed in the top of a container with said flange resting on the top of said container, the capacity of said filling device being substantially equal to the shrinkage upon cooling of a quantity of a given material which at a predetermined elevated temperature is sufficient to fill the container and said filling device. 130 135 140
